ELECTRIC WAVE RECEPTION

George L. Beers, Haddonfield, N. J., assignor to
Westinghouse Electric & Manufacturing Com-
pany, a corporation of Pennsylvania

Original application April 16, 1928, Serial No.
270,285. Divided and this application May 14,
1937, Serial No. 142,559

7 Claims. (Cl. 250—20)

This application is a division of my copending application, Serial No. 270,285, filed April 16, 1928, Patent No. 2,082,478, dated June 1, 1937, and assigned to the assignee of this application.

5 My invention relates to electric wave reception and it has particular relation to the reception and amplification of electric waves at radio-frequencies.

10 Although certain phases of my invention are capable of broad application to radio receiving systems of many types, the invention, considered as an entity, may be regarded as primarily directed toward improving superheterodyne receiving systems of the type disclosed in the patent to Armstrong, 1,342,885.

One object of my invention is to provide a superheterodyne receiving system that shall have improved selectivity characteristics.

20 Another object of my invention is to provide a superheterodyne receiving system in which the so-called "image-frequency response" shall be minimized.

Another object of my invention is to provide 25 a superheterodyne receiving system that shall be substantially incapable of radiating the locally generated oscillations.

Another object of my invention is to provide, in a superheterodyne receiving system of the un- 30 control type, means whereby the tuning of the oscillator stage shall be unaffected by changing the thermionic tube comprised therein.

Another object of my invention is to provide, in a radio receiving system of the aforemen- 35 tioned type, improved inter-tube coupling trans- formers between the thermionic tubes comprised in the intermediate-frequency amplifier.

Another object of my invention is to provide, in a superheterodyne receiving system, improved 40 means for securing the proper frequency relation between the tuning of the oscillation generator and the tuning of the radio-frequency amplifying stages.

Another object of my invention is to provide 45 an improved circuit network for so intercon- necting a plurality of thermionic devices com- prised in a radio receiving system to a source of anode potential therefor that variations in said anode-potential source shall be substantial- 50 ly ineffective to cause variations in the output from said receiving system.

Another object of my invention is to provide 55 an improved circuit network of the aforesaid type that shall comprise means for deriving a plurality

of grid-biasing potentials from the anode-potential source.

Another object of my invention is to provide an efficient volume-control device for a radio receiving system.

5 A superheterodyne receiving system, constructed and arranged according to a preferred embodiment of my invention, comprises a plurality of thermionic devices of the equipotential-cathode type interconnected in cascade through tuned 10 coupling-transformers and supplied with anode potentials and grid-biasing potentials from a rectifying device that may be energized from any convenient source of alternating current. The first amplifying tube of the series is arranged to be coupled to an energy-collecting device through a substantially non-inductive resistor of sufficient magnitude to prevent the antenna from radiating energy from the local oscillator. The resistor does not affect the sensitivity of the system.

15 The thermionic devices comprised in the intermediate-frequency amplifying stages are coupled together through tuned transformers of a novel type. Considered from an electrical standpoint, the intermediate-frequency transformers are so proportioned that they are somewhat analogous to band-pass filters; considered from a mechanical standpoint, they are so mounted in individual shielding devices, and so provided with 20 tuning condensers having easily accessible adjusting elements that they may be accurately calibrated and tuned before being mounted in a complete receiver, with complete assurance that the precalibration will not later be changed.

25 Volume-control is accomplished by varying the grid-biasing potential applied to all of the high-frequency amplifying tubes, such potential being derived from the anode-potential supply through a resistor-network, and the various thermionic 30 tubes comprised in the entire receiving system are so grouped with respect to the said network that a variation of the biasing potential applied to the said high-frequency tubes does not greatly disturb the potential applied to the remaining 35 tubes.

40 I find it preferable to connect all of the main tuning condensers together for simultaneous control, and it is accordingly necessary that the frequency of the oscillations generated by the 45 local oscillator shall not be affected when different thermionic tubes of the same type are substituted therein. I provide for this condition by coupling the frequency-determining circuit of the local oscillator, in which is included one 50 55

of the said maintaining condensers, very loosely to the grid and cathode of the oscillator tube, in order that the grid-cathode capacity of the tube shall be negligible in fixing the frequency to which the said circuit is resonant.

In addition, I have provided a novel arrangement of series and shunting condensers in the frequency-determining circuit of the local oscillator, by the proper adjustment of which a variable tuning condenser of the ordinary concentric-plate type may be utilized to maintain a constant-frequency difference between the local oscillation frequency and the frequency of the incoming signal.

The novel features that I consider characteristic of my invention are set forth with particularity in the appended claims. The invention itself, however, both as to its organization and its method of operation, together with further objects and additional advantages thereof, will best be understood by reference to the following description of a specific embodiment, taken with the accompanying drawings, in which:

Figure 1 is a schematic wiring diagram of a complete radio receiving system comprising a preferred embodiment of my invention;

Fig. 2 is a diagram illustrating the manner in which the various thermionic devices comprised in my improved radio receiving system are supplied with grid-biasing and anode-potentials according to my invention;

Fig. 3 is a perspective view of one of the intermediate-frequency transformers, a portion of the shielding container thereof being broken away;

Fig. 4 is an end elevational view of the transformer shown in Fig. 3;

Fig. 5 is a top plan view of the coil-and-condenser-supporting element of the transformer assembly illustrated in Fig. 3;

Fig. 6 is a cross-sectional view taken along a line corresponding to the line VI—VI in Fig. 5;

Fig. 7 is a plan view of the under surface of the supporting element; and

Figs. 8 and 9 are modifications of the circuit of Fig. 2.

The radio receiving system illustrated in Fig. 1 comprises a thermionic coupling tube 1, a radio-frequency amplifying tube 2, a first detector tube 3, a plurality of intermediate frequency-amplifying tubes 4 and 5, a second detector tube 6, an audio-frequency-amplifying tube 7, and an oscillator tube 8. All of the tubes, with the exception of the audio-frequency amplifier 7, are of the equipotential cathode type illustrated in the patent to Nicolson, No. 1,459,412, and, each tube, excepting the said audio-frequency amplifier, is provided with a grid 9, an anode 10, an equipotential cathode 11, and a heater-element 12. All of the heater elements 12 are connected in parallel, by means of a plurality of conductors 13 and 14, to the terminals of a secondary winding 15 of a power transformer 16, the primary winding 17 of which may be energized from any convenient source of commercial-frequency alternating current.

The audio-frequency-amplifying tube 7 has a filamentary cathode 18 which is arranged to be energized by alternating current supplied from another secondary winding 20 of the power transformer over a plurality of conductors 21 and 22.

The thermionic cathodes 11 of the coupling tube 1, the radio-frequency amplifying tube 2, 75 and those of the first and second intermediate-

frequency-amplifying tubes 4 and 5, are connected together through a conductor 23 which terminates in an intermediate point 24 on a resistor 25, in order to fix their potential with respect to the grids of the several devices and the anodes thereof, in a manner hereinafter specifically described.

The cathode 11 of the first detector tube 3 is connected to the cathode 11 of the oscillator tube 8 over a circuit including a conductor 26 and a coupling-coil 27, the said cathodes, as well as the cathode of the second detector tube 6, being maintained at the same direct-current potential by a common connection 28 to one end of the resistor 25.

The coupling-coil 27 is positioned in inductive relation to an inductor 30 which is comprised in the frequency-determining input-circuit of the oscillator tube 8. A main tuning condenser 31, a vernier condenser 32 in shunt thereto, and a small variable condenser 33 are connected in shunt relation to the inductor 30. The grid of the oscillator tube is variably connected to the inductor 30 through a grid condenser 34 and a stabilizing resistor 35, and a grid-leak 36 is provided to maintain the grid at the proper operating potential.

Anode-potential for the oscillator tube 8 is derived from the positive terminal of a rectifying device later to be described in more detail, the supply circuit including a feed-back inductor 37, positioned in inductive relation to the input inductor 30 which provides the necessary transfer of energy to maintain oscillations therein.

By reason of the inclusion of the inductor 27 in the connection between the cathode of the oscillator tube and the cathode of the first detector tube, the local oscillation frequency is impressed on the first detector tube by causing the potential of its cathode to vary with respect to the potential of the grid, instead of causing the grid potential to vary with respect to the cathode, as is usual. The stability of the system seems to be improved to some extent by this method of connection.

The manner in which the small series adjusting condenser 33 and the shunt adjusting condenser 32 are included in the frequency-determining circuit of the oscillator is an important phase of my invention, since I am thereby enabled to so modify the capacity-displacement curve of the main tuning condenser 31 that a constant-frequency difference may be maintained between the tuning of the oscillator and the tuning of the radio-frequency stages of the amplifier without altering the shape of the oscillator tuning-condenser plates or without shifting the rotor thereof with respect to the stator.

The effective minimum capacity of the tuning condenser may be adjusted by the shunt condenser 32, while the maximum effective capacity of the tuning condenser is determined by the ratio of the series condenser 33 to the total capacity of the tuning condenser and the shunt condenser. By properly adjusting the two added condensers, the curve expressing the relation between the total capacity effective to tune the frequency-determining circuit and the movement of the main tuning condenser may be made to quite closely approximate a predetermined shape. The great utility of the adjusting condensers 32 and 33 will be more apparent hereinafter.

The antenna-coupling tube 1 is provided with an input circuit comprising a resistor 38, one end of which is permanently connected to a

- grounded conductor 40 which terminates in a variable contact device 41 associated with the biasing-potential supply resistor 25. The other end of the input resistor 38 is provided with a connection whereby the said resistor may be included serially in an energy-collecting circuit including an antenna 42 and a ground connection 43. When the resistor 38 is included in the antenna-ground circuit, the antenna is rendered substantially incapable of radiating energy imparted thereto from the local oscillator, either through the coupling tube or through the space outside of the container in which the entire receiving system is mounted.
- 15 A variable contact device 44 may be provided to permit the grid of the coupling-tube to be so connected to the input resistor that the signal-voltage applied to the tube may be altered at will to secure a measure of volume-control.
- 20 Signal-energy from the coupling tube 1 is applied to the input circuit of the radio-frequency amplifying tube 2 through a transformer 45, which is provided with a high-inductance primary constructed according to the disclosure in my copending application, Serial No. 151,722, filed November 30, 1926, which has issued as Patent #1,907,478 of May 9, 1933, and a secondary winding having a variable tuning condenser 46 connected in shunt thereto.
- 25 30 Regeneration in the amplifying tube is controlled through the agency of a feed-back circuit comprising an inductor 47 coupled to the secondary winding of the inter-tube transformer 45, and a small variable condenser 48 connected between the inductor 47 and the anode 19 of the amplifying tube.
- 35 The amplifying tube 2 is coupled to the first detector tube 3 through a transformer 50 having a high-inductance primary winding 51 and a secondary winding 52 shunted by a variable tuning condenser 53 and a fixed condenser 54 in series. The high-inductance primary winding 51 in the output circuit of the amplifying tube causes a certain amount of damping in the input circuit of the said tube, as explained in my aforementioned copending application, which accounts for the necessity of supplying the aforementioned feedback circuit to bring the amplification therein up to the proper value.
- 40 45 The first detector tube 3 is coupled to the first intermediate-frequency amplifying tube 4 through a transformer 55 having a primary winding 56 shunted by a tuning condenser 57 and a secondary winding 58 shunted by a tuning condenser 60. Oscillation in the first intermediate-frequency amplifying tube is prevented according to the method disclosed in the patent to Rice, No. 1,334,118, a small condenser 61, connected between the anode of the tube and the lower end of the secondary winding 58, being utilized to supply the proper anti-oscillation potentials.
- 50 55 The first intermediate-frequency-amplifying tube 4 is coupled to the second intermediate-frequency-amplifying tube 5 through a transformer 62, similar to that interposed between the first detector and the first intermediate-frequency amplifier, and the second intermediate-frequency-amplifying tube 5 is coupled to the second detector tube 6 through another analogous transformer 63. The three transformers 55, 62 and 63, being structurally alike, the several constituent parts of each have been similarly numbered in the drawings. Each transformer is to

tally enclosed by the non-magnetic shielding material, indicated by the dotted rectangles, to minimize interaction between the several amplifying stages.

There is no tendency toward regeneration in the second detector 6, and, for that reason, the neutralizing condenser 61, which is a constituent part part of the transformer-assembly 63, when manufactured, is not needed for neutralizing, and it may, accordingly be connected in shunt relation to the tuning condenser 60, as shown.

10 15 The second detector tube 6 is coupled to the audio-frequency power-amplifying tube 7 through an audio-transformer 70 of any well known type, and the output circuit of the power amplifier may be coupled to a loud-speaker 71 through a blocking condenser 72, as illustrated, or through an output-transformer (not shown).

20 25 The tuning condenser 46, comprised in the input circuit of the radio-frequency amplifying tube 2, the tuning condenser 53 in the input circuit of the first detector tube 3, and the tuning condenser 31 in the frequency-determining circuit of the oscillator tube 8, are all connected together, as indicated by the dotted lines 73, for simultaneous actuation, and the rotors thereof are connected to the grounded conductor 40.

30 35 In order to improve the selectivity of my receiving system, and to minimize the so-called image-frequency response, I have chosen an intermediate frequency of 180 kilocycles, and it is, accordingly, apparent that the frequency of the oscillator must always differ from the frequency of the desired signal by that amount. Manufacturing cost is lessened by giving the same contour to the rotor plates of all the tuning condensers, and by assembling the rotors of the tuning condensers on one shaft but, previous to my invention, this method of construction rendered it substantially impossible to so adjust the system, after assembly thereof into a completed set, that a constant frequency-difference could be maintained over the entire tuning range.

40 45 By providing the aforementioned adjusting condensers 32 and 33, however, the effect of the tuning condenser 31 on the frequency of the oscillations generated by the oscillator may be so materially modified that the desired frequency-difference may be achieved, and maintained over the tuning range, without changing the value of the input inductor 39 or altering the position of the rotor of the oscillator-tuning condenser 31 with respect to the stator thereof, as was the procedure previous to my invention.

50 55 If the oscillator, instead of being tuned to a frequency higher than that of the incoming signal, is to be tuned to a lower frequency, the adjusting condensers 32 and 33 are associated with the input circuits of the radio-frequency amplifier tubes and the first detector tube, and not with the oscillator tube input circuit, as illustrated.

Anode potentials, grid-biasing potentials, and cathode potentials for the various thermionic tubes are supplied from a rectifying device 80 over a network which is arranged according to an important phase of my invention. The rectifying device 80 is of the full-wave rectifying type, having a plurality of anodes 81. The device may be provided with a thermionic cathode 82, supplied with operating potential from a secondary winding 83 on the power transformer 16, or it may be of the cold-cathode type which functions by 75

virtue of gas-action, since the specific rectifier constitutes no part of my invention.

High potential for the anodes of the rectifying device is supplied from a secondary winding 84 on the power transformer, a connecting 85 to an intermediate point on the said winding constituting the negative output-terminal of the rectifier. The positive output terminal of the rectifier, which is constituted by the cathode 82, is directly connected to the anode of the audio-frequency amplifier 7, through a plurality of choke-coils 86, 87 and 88 and a conductor 90. A plurality of by-pass condensers 91 and 92, of relatively large capacities, are connected in shunt to the rectifier output terminals, and provide, together with the choke-coils, a filter circuit to exert a smoothing action on the rectified current.

Anode potential for the coupling tube 1, the radio-frequency amplifying tube 2 and the intermediate-frequency amplifying tubes 4 and 5, is supplied from the positive terminal of the rectifier over a circuit including a resistor 100 and a common conductor 101. Anode potential for the first detector tube 3 and the oscillator tube 8 is supplied from the positive terminal of the rectifier over a circuit including a conductor 102 and a resistor 103 of greater magnitude than the resistor 100, while anode potential for the second detector tube 6 is supplied from the positive terminal of the rectifier over a conductor 104.

In order that the manner in which the rectifier furnishes anode and grid-biasing potentials for the various thermionic devices may be more clearly understood, attention should also now be directed to Fig. 2 of the drawings in addition to Fig. 1. It will be noted that the positive terminal of the rectifier is directly connected to the anode of the audio-frequency amplifier tube 7, and to the anode of the second detector tube 6, thus supplying these tubes with maximum anode potential. Anode potential for the oscillator tube and the first detector are supplied over the resistor 103, one end of which is connected to the conductor 90.

The cathodes of the oscillator tube, the first detector tube, and the second detector tube are conductively connected, by the conductor 28, to an intermediate point on a resistor 105 arranged in shunt to the secondary winding 20, to an intermediate point on a resistor 106 arranged in shunt to the heater-winding 15 and to one end of the previously referred to bias potential resistor 25. The resistor 25 preferably comprises a plurality of fixed resistor elements 107 and 108 and a portion 110 with which is associated the movable contact device 41, one end of the portion 110 being directly connected to the negative terminal 85 of the rectifying device.

The sum of the space currents in the oscillator tube, the first and second detector tubes and the audio-frequency amplifying tube, therefore, flows through the entire resistor 25, and causes a fall in potential thereacross, the end nearest the rectifier terminal 85 being obviously the negative end. Since the cathodes of the tubes just referred to are all connected to the positive end of the resistor 25, the grids of the tubes may be given appropriate negative biasing potentials by connecting them to points along the resistor element 101, as illustrated. It is preferable, however, to so arrange the oscillator that no initial bias be applied to the grid thereof and the grid resistor 36, therefore, is connected directly to the cathode 11.

The cathode of the coupling tube, the radio-

frequency amplifying tube and the two intermediate-frequency amplifying tubes are connected to a point on the resistor 25 intermediate the sections 107 and 108, and a resistor 120 is connected in shunt to the space-current paths of the said tubes. The fall in potential across the resistor sections 108 and 110 is accordingly in part fixed by the current flowing through the resistor 120, in part by the space-current in the high-frequency amplifying tubes 1, 2, 4 and 5, and in part by the space-current in the remaining tubes. By choosing proper values for the resistor 120 and the resistor section 108, the potential of the contact-device 41 may be maintained highly negative, notwithstanding marked variation in the space currents from the several tubes.

The contact device 41 may, accordingly, be utilized to vary the magnitude of the negative potential applied to the grids of the high-frequency amplifying tubes 1, 2, 4 and 5, for volume-control purposes while the system is in operation, with the full assurance that an ample negative potential is always available.

In some instances, particularly when my improved receiving system is operated relatively close to a powerful broadcasting station, it is necessary for complete volume-control, to provide means whereby the grid of the coupling tube 1 may be given a more negative bias than the grids of the succeeding amplifying tubes. This may be accomplished by providing a separate variable connection 173 from the cathode of the coupling tube to the resistor 25, whereby upon movement of the contact device 41 toward the negative end of the resistor element 110, the said variable connection is caused to simultaneously move toward the positive end of the resistor. Another way in which I may accomplish the same result is to connect the shunting resistor 120 with thermionic tubes 1 and 2 alone, and to supply the tubes 4 and 5 with anode potential across a separate resistor 175, at the same time retaining the remaining connections as illustrated in Fig. 2. The modified circuit is illustrated in Fig. 9.

In either event, the shunting resistor 120 has the very important function of preventing an undue increase in the plate potential applied to the high-frequency amplifying tubes when they are so negatively biased as to diminish the space currents therein.

Thus it is clear from the above description that the resistor 120 is of such a value as to maintain a substantially unvarying anode potential upon the anodes of the tubes 1 and 2 during changes of grid bias, and in order that the circuit should function in the desired manner, namely, to obtain a greater change in amplification in the preceding tubes of the cascade arrangement than in the succeeding tubes, it naturally follows that the anode potential of the tubes 4 and 5 must not be maintained substantially unvarying whereas with reference to the tubes 1 and 2, the anode voltage must be permitted to fluctuate in response to changes in the plate current brought about by the changes in the grid bias of the succeeding tubes 4 and 5. As the grid bias on these tubes is increased, the plate current will decrease and the voltage impressed upon the anodes of these tubes will increase. The result is that the change in amplification of tubes 4 and 5 will be smaller and at a lower rate than the change on the preceding tubes 1 and 2 in the cascade arrangement. In the latter precautions have been taken to avoid

substantial changes in the voltage impressed on the plates.

A bypass condenser 130 is connected in shunt with the resistor 120 in order that potential fluctuations impressed thereacross shall not be effective to interfere with the action of the succeeding devices in the series.

A similar bypass condenser 131 is connected in shunt with the space-current paths of the oscillator and first detector tubes for an analogous purpose.

Additional bypass condensers 132, 133 and 134 are provided for the purpose of forming low-impedance paths around the resistor assembly.

The variable contact device 111, or volume control, is provided with a connection to ground, and to the chassis of the set, for safety purposes.

An important phase of my invention is concerned in the construction and arrangement of the intermediate-frequency coupling transformers 55, 62 and 63, which are shown in detail in Figs. 3 to 7, inclusive, of the drawings, in order that the intermediate stages may have the requisite selectivity and yet not be so sharply tuned that the quality of the signals is impaired.

Each of the intermediate-frequency transformers comprises an insulating plate 140 which rests upon, and is supported by, two of the upper edges of a metallic shielding container 141. The container, which is preferably rectangular in form, is provided with a plurality of upwardly-extending ears 142 adapted to be inserted upwardly through openings in a metallic frame element incorporated into the chassis of the set (not shown), and bent over to maintain the container firmly in position.

The primary winding 56 and the secondary winding 58 are coaxially mounted on an insulating form 150 which is suspended from the cover plate 140 by means of a plurality of angularly bent arms 151. The coupling between the windings may be varied within the limits of the length of the form for a purpose hereinafter described more in detail.

The fixed primary tuning condenser 57 is mounted on the upper surface of the insulating plate and is fastened thereto in any desired manner, the said condenser being connected across the terminals of the primary winding by means of a plurality of conductors 152 and 153.

In addition to the fixed tuning condenser, the variable secondary tuning condenser 60 and the variable neutralizing condenser 61 are also carried by the cover plate, being mounted on opposite sides thereof.

Referring specifically to Figs. 5, 6 and 7, the variable tuning condenser 60 comprises an immovable plate 154 held to the upper surface of the cover-plate 140 by a plurality of solid rivets 155, and a flexible element 156, one end of which is affixed to the cover-plate by means of a hollow rivet 157. The upper end of the hollow rivet extends through an opening in the bottom of a small cup 160, thus holding the cup and the end of the flexible element firmly in contact.

The variable neutralizing condenser 61 comprises an immovable plate 161 held to the under-surface of the cover-plate 140 by a plurality of solid rivets 162, and a flexible element 163, one end of which is affixed to the cover-plate by means of a hollow rivet 164 having an interior thread.

An adjusting screw 165 extends downward through the hollow rivet which holds the end of the upper movable plate 156 in position and cooperates with a nut 166 affixed to the free end

of the lower flexible element 163 to provide adjusting means therefor.

A small cup 167, having an opening through the bottom thereof, is affixed to the free end of the upper flexible element 156 by a hollow rivet 168 through which extends an adjusting screw 170 that engages the interiorly threaded surface of the rivet 164, thus holding the end of the lower flexible element in position. The upper movable element of the condenser 60 may, accordingly, be adjusted with reference to the fixed plate thereof by rotating the said screw.

The terminals of the tuning condenser 60 and the neutralizing condenser 61 may be connected to lugs 171 mounted on the edges of the cover-plate, or to the proper terminals of the primary and secondary windings, as shown in Fig. 1.

The small cups 163 and 167 are filled with sealing-wax, or an analogous material, after the condensers have been properly adjusted, which partially prevents subsequent tampering with the adjustment. Tampering with the condenser adjustment is still further prevented by the novel manner in which the shielding containers are mounted beneath the chassis of the set, as hereinbefore described.

When both the primary winding and the secondary winding of the transformer are properly tuned, and the coupling between the windings adjusted, it is found that the resonance curve thereof has a sufficiently wide peak to permit the efficient amplification of the side-band frequencies, a feature that is noticeably lacking in air-core intermediate-frequency transformers constructed previous to my invention.

Insofar as I am at present aware, it has not been previously suggested that economy of space and convenience in adjustment could be obtained by so mounting a plurality of variable condensers on the casing of an intermediate-frequency transformer that each of said condensers could be separately and independently adjusted from the exterior of the said casing. In addition, since the condensers are completely shielded electrically from other parts of the receiving system, when the container is mounted in place beneath the chassis, the opportunity for inter-circuit coupling, and consequent regeneration, is eliminated.

The space between the transformer windings and the inner walls of the shielding container is preferably filled with an insulating compound, a mixture of beeswax and resin having been found very desirable for this purpose.

I have determined, by careful experiments, that, by utilizing my improved intermediate-frequency transformers in a superheterodyne receiving system, the amplification obtainable is greatly increased. Many factors enter into the improvement in amplification, the shortness of leads, the tuning of both primary and secondary, the complete shielding, and others which I have not, as yet, fully determined. Since the amplification, however, is improved, I am enabled to employ an intermediate frequency of the order of 180 kilocycles with good results, instead of the usual 40 kilocycle frequency, and the use of the high intermediate frequency very greatly reduces the "image-frequency" response of the system. By "image-frequency" response is meant the response of the system to an undesired signal which differs in frequency from the desired signal by twice the intermediate frequency. If, therefore, the intermediate frequency is high, the selectivity of the radio-frequency stages of the system will be such as to greatly reduce, in am-

plitude, any signal which differs from the desired signal by twice the said intermediate frequency.

It will, accordingly, be apparent that the several phases of my invention cooperate to enable the production of a superheterodyne receiving system that is superior, in many respects, to analogous receiving systems constructed according to the teachings of the prior art.

I am aware that many modifications of my invention may be suggested to persons skilled in the art, and that many other specific embodiments thereof are possible. My invention, therefore, is not to be limited except insofar as is necessitated by the prior art and by the spirit 10 of the appended claims.

I claim as my invention:

1. In combination, a source of fluctuating unidirectional potential, a thermionic device arranged to amplify electric currents at high frequencies, a resistor, connections whereby said resistor and the space-current path in said device are serially included in shunt to said source, a thermionic device arranged to amplify electric currents at audio-frequencies also having its space-current path connected in shunt to said source, and an impedance device interposed between the point of connection of said first-mentioned device to said source and the connection of said second-mentioned device to said source, whereby said first mentioned device tends to materially reduce the fluctuating component of the potential applied to said second-mentioned device.

2. In combination, a source of fluctuating unidirectional potential, a thermionic device arranged to amplify electric currents at frequencies higher than audio-frequencies, a resistor, connections whereby said resistor and the space-current path in said thermionic device are serially included in shunt to said source, a second resistor connected in shunt to said space-current path, a thermionic device arranged to amplify electric currents at audio-frequencies, an impedance device, connections whereby said second-mentioned thermionic device and said impedance device are serially included in shunt to said source, and means for deriving a grid-biasing potential for said first-mentioned device from the space current therein and from the space current in said second-mentioned device.

3. In an electric-current-amplifying system, a plurality of thermionic devices interconnected through tuned transformers and adapted to amplify electric currents at frequencies higher than

audio-frequencies, a plurality of thermionic devices arranged to function as demodulators, a thermionic device arranged to function as an oscillation generator, a thermionic device arranged to amplify the output of one of said demodulators, and means whereby the space current flowing in said demodulators, said oscillation generator and said audio-frequency amplifier is utilized to provide grid-biasing potentials for said first-mentioned thermionic devices.

5

4. In an amplifying system employing electron discharge devices in cascade, said devices having control grid and other electrodes, the method of controlling amplification which comprises increasing the negative bias on the control grid electrodes of certain of said devices to produce a decrease in amplification and simultaneously increasing the positive voltage on another electrode of one of said tubes tending to increase amplification.

10

5. The method of operating an amplifier system constituted by a plurality of amplifying devices connected in tandem, which comprises applying a gain control potential to said devices, applying a second gain control potential to a lesser number of said devices than said first gain control potential, causing the first-mentioned potential to vary and causing the second-mentioned potential to simultaneously vary with variations 15 in the first-mentioned potential.

20

6. In an amplifying system employing electron discharge devices in cascade, said devices having control and other electrodes, the method of controlling amplification which comprises increasing the negative bias on the control electrodes of certain of said devices to produce a decrease in amplification and simultaneously increasing the amplification of a lesser number of devices beyond the first device in said cascade by increasing the positive voltage on another electrode of said lesser 25 number of devices.

30

7. The method of operating an amplifier system constituted by a plurality of amplifying devices connected in tandem, which comprises applying a gain control electrical quantity to said 35 devices, applying a second gain control electrical quantity to certain of said devices after the first, causing the first gain control quantity to vary the amplification of said devices in one direction and simultaneously causing said second gain control quantity to vary the amplification of said 40 certain devices in the opposite direction.
